UNITED STATES PATENT OFFICE.

ALBERT E. WIGGIN, OF ANACONDA, MONTANA, ASSIGNOR OF ONE-THIRD TO ULYSSES A. GARRED AND ONE-THIRD TO FREDERICK LAIST, BOTH OF ANACONDA, MONTANA.

MULTIPLE-DECK CONCENTRATOR.

1,078,977.

Specification of Letters Patent.

Patented Nov. 18, 1913.

Application filed April 7, 1913. Serial No. 759,463.

To all whom it may concern:

Be it known that I, ALBERT E. WIGGIN, citizen of the United States, residing at Anaconda, in the county of Deerlodge and 5 State of Montana, have invented certain new and useful Improvements in Multiple-Deck Concentrators, of which the following is a full, clear, and exact description, reference being had to the accompanying drawings, forming a part hereof.

My invention has relation to improvements in multiple-deck concentrators and pulp distributers therefor; and it consists in the novel features of construction more 15 fully set forth in the specification and pointed out in the claims.

In the drawings, Figure 1 is a middle vertical section taken through the concentrator, the pulp-feed-pipes for some of the 20 decks being broken away for the sake of clearness, certain parts being in elevation; Fig. 2 is a horizontal section on the line 2—2 of Fig. 1 taken below the bottom deck; Fig. 3 is a horizontal section on the line 3—3 of Fig. 1 taken above the deck-frame; Fig. 4 is a horizontal section (partly broken) on the zig-zag line 4—4 of Fig. 1 taken above the two bottom decks of the series; Fig. 5 is an enlarged middle vertical section taken at 25 right angles to the showing in Fig. 1, of the two upper decks of the concentrator and their cooperative parts, the bottom of the distributer and feed-pipes leading therefrom being in elevation; Fig. 6 is an enlarged radial vertical section taken through one of the decks, the said deck being broken at an intermediate point; Fig. 7 is a bottom plan of a portion of a deck, parts being removed to expose the inner reinforcing expanded metal layer; Fig. 8 is a front elevation of the pulp-distributer on an enlarged 40 scale; Fig. 9 is a side elevation thereof; Fig. 10 is a middle vertical section of the distributer-tank showing also the bottom discharge of the rotatable pulp-intake and distributing pipe; and Fig. 11 is a top plan of the distributer-tank.

The present invention is specially directed to improvements in rotatable slime concentrators, the main object thereof being to provide a concentrator in which a plurality of decks or tables for the treatment of the slimes are disposed vertically over one another, that is to say in vertical series, and

spaced sufficiently apart to afford access to 55 the individual decks, the entire series rotating as a unit about a common vertical axis.

A further object is to provide suitable means of access to any deck from a point adjacent the axis of rotation of the concentrator, special provision being made for this purpose in the form of an axially disposed passage-way or "well" through the concentrator, or series of decks composing the same.

The invention further contemplates among the objects sought, the use of an available pulp distributer whereby it is possible to accord to the several decks at all times, an equal quantity of pulp, the pulp 70 supplied to the concentrator being evenly distributed among the several decks.

A further object is to provide means for maintaining this even distribution of pulp among any number of decks operating at 75 any time, irrespective of the fact that one or more decks of the series may be temporarily cut out of commission.

The invention possesses further and other features the advantages of which will be 80 readily apparent from a detailed description thereof which is as follows:—

Referring to the drawings, B represents a suitable preferably concrete foundation along the top of which is disposed a circular 85 track or rail R. At points exterior to and at uniform distances from the track are disposed a series of vertical structural members 1, 1, carrying along their inner faces suitable discharge launders 3 as shown, the 90 tops of the members 1 extending to the roof timbers 4 or their equivalents, the parts 1 thus forming a rigid stationary frame or housing for the rotating concentrator-decks supported by the track R.

As above stated, the concentrator is composed of a plurality of superposed decks D, the concentrating surfaces of which are preferably conical as shown and sloping downwardly and outwardly (though a conoidal 100 surface, with or without depressions or pools, or any equivalent thereof would not be falling outside the scope of my invention). Each deck is provided with a central opening O disposed symmetrically about the axis 105 of the deck, the succession of openings forming a vertical passage-way or "well" W, through the multiple-deck concentrator.

The concentrating surface of the deck may be composed of any well known material, for example wood, linoleum, canvas, rubber, concrete and the like, preference being herein shown for concrete. To insure stiffness and at the same time comparative lightness for the deck I construct the same as shown in detail in Fig. 6, that is to say with an inner ring or hub *a*, an outer ring *a'*, radial stiffening and connecting angle-bar members or ribs *b*, the latter having deposited thereover and secured thereto a metallic sheet or plate *c* on which is deposited a layer of concrete *d* reinforced by a sheet of expanded metal *e* serving as a binder, any suitable mechanical means of securing the parts together being resorted to. A construction of the kind here availed of necessitates a comparatively thin layer of concrete.

The several decks are supported at their peripheries by lugs or brackets *5* disposed in superposed horizontal planes on the vertical double-angle or equivalent structural members *6* forming the outer columns of the rotatable steel frame with which the decks are identified. In lieu of lugs or brackets any equivalent means may be employed to secure the decks to the columns. The outer portions of the decks are cut away forming recesses *r* for the reception of the columns *6*, the edge of the plate *c* of the deck being provided with a depending rim *c'* over which the concentrates, sands, and tailings discharge into their respective compartments in the outer launders *3*. The upper ends of the columns *6* are connected to an outer ring *7* which is in turn coupled to an inner ring *7'* through a series of radial members or braces *8*. The bottoms of the columns *6* are connected to an outer ring *9* which is in turn coupled to an inner flanged ring *9'* through a series of radial members *10*.

It will be seen from the foregoing that the rotatable steel deck-frame constructed as here outlined is not only comparatively light but is rigid, the principle of its construction permitting it to be run up to considerable height to accommodate a reasonable number of decks. In the present illustration are shown ten decks, but twenty decks could readily be improvised by extending the frame to the proper height, any apparatus containing two or more decks falling within the spirit of my invention so far as it relates to the plurality feature of the decks. To the ring *9* and braces *10* are secured forked brackets *11* in which are mounted the wheels or rollers *12* traversing the track *R*. In this way the entire concentrator is rotatable about its vertical axis, the several decks rotating as a unit about said axis. The manner of imparting rotation to the concentrator is immaterial, the means herein shown comprising a motor *M* the shaft-pinion *13* of which meshes with a gear wheel *14* on a

parallel shaft *15* which carries a pinion *16* meshing with a gear wheel *17* on a shaft *18* mounted in bearings *19*. The shaft *18* actuates through a worm pinion *18'* (partly obscured by the member *10*) a horizontal worm-gear *20* carried by a vertical shaft *21* in the bearing *22* the upper end of the said vertical shaft carrying a grooved pulley *23* from which passes a drive-belt *24* over the periphery of the ring *9'*. The driving mechanism is illustrated more or less conventionally and may be varied to suit the convenience of the operator or to suit conditions. Means for holding the parts rigid though illustrated in the drawings are not however referred to as they are mere mechanical expedients to be changed at pleasure, their location and construction falling within the purview of the skilled mechanic. It will be seen that by starting the motor, rotation will be imparted to the series of decks revolving as a unit about a common vertical axis.

Resting on the foundation *B*, and passing through the well *W* and running upward to the roof or overhead timbers *A*, is a square tower *T* built of steel structural members, any side of the tower serving as a ladder by which access may be had to any deck *D* of the series. The tower likewise serves as a means to support the feed-launders and in a measure to support the pulp-distributing and wash-water pipes playing over the several decks. Mounted above each deck *D*, around the central opening *O* thereof, and preferably supported by angle-brackets *25* secured to the tower *T*, are pulp-feed launders or boxes *3'* the same being preferably of the cross-section as shown (having three concentric walls) and substantially circular in form, and open at one end to discharge the pulp onto the deck or table, each launder having disposed across the same at a convenient point a transverse partition *25'* (Fig. 4) closing the launder at that point, the launder portion exterior to said partition being availed of to receive and discharge the necessary complement of wash water for washing down the sands and tailings toward their respective compartments *t*, *t'*, *t''*, *t'''*, into which the launder *3* is divided to receive the various products of concentration according to their gravities, each compartment being provided with a discharge tube *26* controlled by a valve *V* for the discharge of its contents. As well understood in the art the heaviest concentrates will remain longest on the concentrating surface from which they are dislodged and washed by special water streams into a special compartment *h* of the launder *3* likewise provided with a valve-controlled discharge pipe *26*.

Obviously, the most practical manner of conducting the pulp and water to the several decks is through the well *W*. Accord-

- ingly I lead through said well and on the outside of the tower T, a series of pulp-feed pipes 27 the upper ends of which are coupled by means of unions 28 to the discharge nipples 29 at the bottoms of the compartments 29 of a pulp distributor or tank 30 mounted conveniently directly over the center of the concentrator, the upper ends of the feed-pipes being suitably bent so as to permit the majority of the cluster of pipes to be led through the space in the well opposite one of the sides of the tower T, although where there are many pipes, some of them might have to be distributed around the tower in one or both of the contiguous spaces. The distributor-tank 30 has as many compartments as there are decks D, so that each compartment takes care of its own particular deck, the feed-pipes increasing in length as they approach the bottom of the concentrator, the closed bottom of every pipe terminating opposite its respective deck. From a suitable fitting 31 at the closed end of each pulp-feed pipe there radiate a series of branches 27' the free ends of which dip downwardly and discharge into the launder 3', the pipe 27 being provided at a point above the fitting 31 with a gate-valve G or its equivalent whereby the pulp may be cut off from or turned into the branches and hence cut off from or turned onto any deck of the series, access to such valve being had through the interior of the tower. The branches 27' necessarily cut across the space on the inside of the tower (Figs. 3, 4) but not sufficiently to interfere with the movements of the average size workman, it being remembered that the tower is between two and three feet square.
- Passed upwardly through one corner of the tower is a water-feed pipe 32 supplied with water under pressure from any available source (not shown) the upper closed end of the pipe terminating above the top deck (Fig. 5). Leading from the pipe 32 at points above each deck are branches 32', 32'' (the branch 32' tapping the branch 32'') controlled by valves 33, 34, respectively, the branch 32' being bent to discharge water into the launder 3' outside the partition 25' whereby the water and pulp mingle as they reach the concentrating surface of the deck D, the branch 32'' reaching over the deck between the ends of the feed-launder (Figs. 3, 4) and direction forcible jets from nozzles 35 said jets washing the heavy concentrates into the compartment *k* of the discharge launder 3, whence they are in turn discharged through the pipe 26. It will be seen that all valves are accessible from the inside of the tower or "ladder" T, and hence every deck of the series is under ready control of the operator.
- The object of course, is to cause an equal distribution of pulp among the several decks during the operation or rotation of the concentrator, whether all the decks are in commission or not. As stated above, the pulp-feed pipes lead from the compartments 29 of the distributor 30, and it accordingly becomes necessary that each compartment or "section" of the distributor shall receive as much pulp as its neighbor, if each deck or table is to receive its proper proportion of pulp. To effect this equal distribution among the several decks I make the following provision: Mounted in a suitable bearing 36 secured to the timbers A' above the fixed concentrator housing, and on the extension of the axis of the tank 30 is a rotatable pulp-intake and distributing pipe 37 terminating at its lower end in an inclined discharge member 37' which sweeps circularly across the series of the radially disposed compartments 29 of the tank 30, thereby delivering (assuming the pipe 37 rotates at a uniform speed) an equal proportion of pulp to each compartment. The upper end of the pipe terminates in a funnel or flaring mouth 38 into which the pulp is conducted from any original source of supply (not shown). The preferred manner of imparting rotation to the pipe 37 is as follows:—Below the funnel 38 is secured to the pipe a bevel pinion 39 which is in mesh with a similar pinion 40 at one end of a horizontal shaft 41 mounted on the top of the standards 42, the opposite end of the shaft being provided with a belt-pulley P to which rotation may be imparted from any suitable source of power (not shown). As shown to best advantage in Figs. 10, 11, the upper edges of the partitions *p* separating the compartments 29 converge toward a central basin 43 which takes care of the overflow from any compartment when that compartment and the deck corresponding thereto are put temporarily out of commission by the closing of the valve G of the feed-pipe leading from said compartment. The pulp which is discharged from the member 37' into the compartment thus temporarily out of commission finds its way into the basin 43 whence it overflows in equal proportions into the remaining compartment, or those not cut off from their respective decks thereby under all circumstances insuring an equal distribution or pulp-apportionment among the several decks which are in actual service; and from what has just been pointed out it makes no difference whether all decks are in operation or only a portion of them, the equal pulp apportionment resulting from the action of the distributing member 37' alone when all decks are engaged, and from the conjoint action of said member and the basin 43 when one or more of the decks have been cut out.
- The operation of the concentrator is substantially as follows:—The motor M being

started, rotation is imparted to the series of decks D (see arrow Fig. 4) and at the same time rotation is imparted to the pipe 37 pulp being at the same time discharged thereinto through the funnel 38 from any suitable source of supply. The pulp discharges from the terminal 37 successively into the various compartments 29 of the tank 30, each compartment receiving its proper portion of material, the latter discharging through the pipes 27 onto the feed launders 3' of the several decks, whence it runs over the decks mingling with the water from the branches 32', the various products of concentration (tailings, sands, and the like) finding their way into their respective compartments t , t' , t'' , t''' , of the discharge launders 3. The heavy concentrates are removed by the water sprays from the nozzles 35 of the branches 32'' as clearly obvious from the drawings, the valves V of the several launder compartments providing for the escape of the classified materials. In the event any deck (or decks) is put out of commission by the closing of a valve G, the overflow or excess of pulp intended for that deck is caught in the basin 43 whence it overflows in equal proportions into the compartments 29 identified with the pipes 27 leading to the active decks or those still in commission, so that under all circumstances is the pulp distributed in equal proportion among the decks which happen to be working irrespective of their number. Of course, if the supply of pulp to the funnel 38 is constant and uniform, the cutting out of any deck, while causing more pulp to flow over the remaining decks, will insure the equal distribution thereof among the decks which happen to be in service. Access to any of the valves or decks may always be had through the tower or ladder T positioned within the "well" of the concentrator. The details here shown and described need not of course be adhered to, any desired changes falling within the purview of the skilled mechanic being herein contemplated. Having described my invention, what I claim is:—

1. A multiple-deck concentrator comprising a series of columns disposed about a fixed vertical axis, suitable formations disposed in superposed horizontal planes on said columns, concentrating decks located in the space within the columns and supported at their outer edges on said formations, the several decks having openings collectively forming a central well through the decks, the concentrating surfaces of the decks sloping outwardly and downwardly toward the supporting formations aforesaid, an outer rigid frame surrounding the decks, discharge launders on said frame for receiving the material from the decks, a tower in the

well, pulp-feed launders supported from the tower above the several decks, at points adjacent the well, and means for supplying pulp to the several feed-launders.

2. A multiple-deck concentrator comprising a series of columns disposed about a fixed vertical axis, outer rings coupling the adjacent terminals of the columns, suitable upper and lower inner rings, radial braces connecting the inner rings to their adjacent outer rings, thereby forming a suitable frame, means for imparting rotation to said frame about the axis aforesaid through one of the inner rings, a circular track disposed adjacent the bottom outer ring, a series of rollers disposed at the outer portions of the bottom of the frame and traveling on said track, brackets on the columns disposed in superposed horizontal planes, suitable decks having concentrating surfaces sloping downwardly toward the brackets, and supported by the latter within the rotatable frame, the decks being provided with central alining openings forming a well through the decks, a tower in said well, a series of pulp-feed launders supported from the tower over the inner portions of the decks, an outer rigid stationary frame, discharge launders secured thereto for receiving the discharges from the decks, and means within the well for supplying pulp to the feed-launders of the individual decks.

3. A multiple-deck concentrator comprising a series of columns disposed about a fixed vertical axis, outer rings coupling the adjacent terminals of the columns, suitable upper and lower inner rings, radial braces connecting the inner rings to their adjacent outer rings, thereby forming a suitable rigid frame, means for imparting rotation to said frame about the axis aforesaid through one of the inner rings, a circular track disposed below the outer bottom edge of the frame, wheels on said frame traveling on said track, a series of decks having outwardly and downwardly sloping concentrating surfaces superposed within the frame and spaced apart, means on the columns disposed in superposed horizontal planes for supporting the several decks at their outer peripheries, the decks being provided with central alining openings collectively forming a well through the decks, a tower in the well, pulp-feed launders supported from the tower over the inner portions of the respective decks, an outer stationary frame, discharge launders secured thereto for receiving the discharges from the decks, water-pipes within the tower, branch-pipes leading therefrom through the tower and discharging over the decks, and means within the well for supplying pulp to the several pulp-feed launders.

4. In a multiple-deck concentrator, a series of columns disposed circularly about a fixed

vertical axis, means for coupling the adjacent ends of the columns together, upper and lower inner rings disposed about said axis, braces leading from said rings to the 5 adjacent ends of the columns, thereby forming a rigid frame, a series of decks superposed within the frame and having their outer edges supported by the columns, the concentrating surfaces thereof sloping outwardly and downwardly toward their points 10 of support on the columns, the decks being provided with central alining openings forming a well through the decks, as set forth.

15 5. A multiple-deck concentrator comprising a series of columns disposed about a fixed vertical axis, suitable formations disposed in superposed horizontal planes on said columns, concentrating decks located in 20 the space within the columns and supported at their outer edges on said formations, the several decks having openings collectively forming a central well through the decks, the concentrating surfaces of the decks sloping outwardly and downwardly from said well toward the supporting formations 25 aforesaid, pulp-feed launders, means within the well for supporting said pulp-feed launders, and means for supplying pulp to 30 the feed-launders.

35 6. A multiple-deck concentrator comprising

ing a series of columns disposed about a fixed vertical axis, suitable formations disposed in superposed horizontal planes on said columns, concentrating decks located in 35 the space within the columns and supported at their outer edges on said formations, the several decks having openings collectively forming a central well through the decks, the concentrating surfaces of the decks 40 sloping outwardly and downwardly from said well toward the supporting formations aforesaid.

7. A multiple-deck concentrator comprising a series of columns disposed about a 45 fixed vertical axis, a series of superposed decks located in the space within the columns, means for securing the decks to said columns at points adjacent the peripheries of the decks, the several decks having 50 openings collectively forming a central well through the decks, the concentrating surfaces of the decks sloping outwardly and downwardly from 55 said well toward the peripheries of the decks.

In testimony whereof I affix my signature, in presence of two witnesses.
